FIG. 1

FIG. 2

FIG. 3

INVENTOR.

EDWARD A. WRIGHT

BY *B. F. Funk*

ATTORNEY.

UNITED STATES PATENT OFFICE

EDWARD A. WRIGHT, OF WICHITA, KANSAS

BOAT

Application filed October 27, 1930. Serial No. 491,335.

This invention relates to boats and particularly to the body of the boat.

The primary object of the invention is to provide a boat having a top and bottom which co-act to maintain the minimum of submergence in the water when the boat is being propelled, this being accomplished by providing a bottom adapted to give the maximum impact lift to the boat in the water and a top which will give a suction lift to the boat. The profile of the boat is generated on a modulated curve and the water line contour as well as the normally submerged lower portion of the boat is generated on a parabolic curve to offer the least impact resistance or frictional resistance by the water to the boat as it is propelled therethrough.

The nose of the boat is generated on a curve to present the least amount of resistance to the air and water and inasmuch as the boat has both a water lift and an air lift due to the impact of the water and the air, the degree of submergence in actual practice will be practically nil and since the sides of the boat are curved to provide the least resistance, the speed of the boat will be enhanced. Means is provided for guiding the boat, a separate means is provided for raising and lowering the nose or bow of the boat and additional means is provided for effecting banking or sudden turns.

The novelty of the invention will be understood by reference to the following description in connection with the accompanying drawings in which:

Fig. 1 is a plan view of the boat.

Fig. 2 is a side elevational view of the same and

Fig. 3 is a cross-sectional view on the line 3—3 of Figure 2.

By reference to the drawings, it will be observed that the bow or nose of the boat is generated on a parabolic curve with the top of a greater curvature than the bottom and that the tail or stern of the boat comes to a

relatively sharp point where the rudder is located and a trailing wheel and water rudder is supported.

The bottom 1 from the bow to the stern has a relatively shallow dip 2, slightly curved upwardly toward the stern. The top from the bow to the cock-pit 3 is generated on a relatively wide curve as indicated at 4 and from the cock-pit to the stern, the top is generated on a relatively shallow curve 5. The sides 6 and 7 are symmetrical from the bow to the stern in that they are both alike, the widest portion of the boat being substantially at the front of the cock-pit. Within the cock-pit is a seat 8 upon which the operator sits to steer the boat from the rudder bar 9 connected by flexible cords or cables to the rudder post 10. To the upper end of the post 10, outside the hull, is a wind rudder 11 and connected to the lower end of the post, outside the hull, is a stern-supporting wheel and rudder 12. The operator is, therefore, enabled to steer the boat by the use of his feet. The boat can be propelled by a propeller 13 driven by an engine 14 within the hull in a well known manner.

Near the stern of the boat are two pivoted, connected, normally horizontal fins or rudders 15 and 16 on a shaft 17 adapted to be turned through a cable 18 within reach of the operator and near the middle or waist portion of the boat are two independent horizontal water fins 19 and 20 having aileron action so that they can be tilted in opposite directions for banking or making sharp turns. The normal water line of the hull is indicated at 21.

For a 12-foot boat, the following dimensions above and below the line 22 are recommended for the side ribs:

Percent	Upper	Lower
0	000	000
1 $\frac{1}{4}$	6.24	2.70
2 $\frac{1}{2}$	9.60	4.38

Per cent	Upper	Lower—Cont'd.
5	14.52	5.88
7½	18.36	6.18
10	21.42	6.96
15	25.68	8.34
5	29.74	8.58
30	31.72	8.82
40	31.50	8.28
50	29.34	7.26
60	25.68	6.12
10	20.64	4.98
80	14.76	3.72
90	8.04	2.40
95	4.50	1.68
100	000	000

15

Side elevation 12' cord

In other words, the table above gives the preferred side elevation cord for a 12-foot boat and the following table gives the top elevation cord for the same boat:

Per cent	Upper	Lower
0	000	000
25	4.72	4.72
1¼	6.58	6.58
2½	8.94	8.94
5	10.96	10.96
7½	12.49	12.49
30	14.34	14.34
10	15.36	15.36
20	15.86	15.86
30	15.90	15.90
40	13.90	13.90
50	11.82	11.82
55	9.38	9.38
60	6.68	6.68
70	3.70	3.70
80	2.02	2.02
40	100	000

85

Top elevation 12' cord

In actual practice, the up-lift impact of the water will give a lift to the boat and the negative pressure created by splitting the air by the boat will cause the air to exert a suction lift so that the hull will skim along the surface of the water with the least degree of submergence and the stream line body of the boat will give the maximum amount of water slip so that wave impact or side friction will be reduced to a minimum.

What I claim and desire to secure by Letters-Patent is:—

1. A boat body consisting of a hollow member, inclosed except for a cock-pit opening, the bow of the boat being generated on parabolic curves, a rudder at the stern of the boat depending from the bottom, a rudder at the stern projecting from the top, a pair of connected, horizontally pivoted rudder members in front of the first named rudder members and a pair of independently movable, horizontal, flat members project-

ing from the sides of the boat near the middle portion thereof.

2. A boat consisting of a hollow member having a parabolic profile having a blunt bow curved upwardly and downwardly with a bottom curved downwardly and then upwardly and sides curved outwardly and then inwardly so that the stern of the boat is relatively narrower than the bow, the shape coefficient of the lower cord having definite relation to the shape coefficient of the top cord of the body so as to split the air when the boat is in motion to create pressure on the bottom and suction lift at the top.

In testimony whereof I affix my signature.

EDWARD A. WRIGHT.
